(57) **CLAIM**

We claim the ornamental design for a pocket case for mobile communications device, as shown and described.

DESCRIPTION

FIG. 1 is a front perspective view of a pocket case for mobile communications devices According to the present design

FIG. 2 is a back perspective view thereof.

FIG. 3 is a back plan view thereof.

FIG. 4 is a front plan view thereof.

FIG. 5 is a side elevation view thereof.

FIG. 6 is a side elevation view thereof, the side being the side opposite of the side shown in FIG. 5.

FIG. 7 is a top elevation view thereof; and,

FIG. 8 is a bottom elevation view thereof.

The broken lines depicting portions of a mobile communications device represent environmental subject matter that forms no part of the claimed design. The broken line features on the side surfaces of the article represent portions of the case for a mobile communications device that form no part of the claimed design.
